RECLINING CHAIR

George C. Mulhauser, Jr., 545 Clinton Road,
Paramus, N.J. 07652

Filed Oct. 12, 1966, Ser. No. 4,247

Term of patent 14 years

(Cl. D15—11)

FIGURE 1 is a side elevational view of a reclining chair showing my new design,

FIGURE 2 is a perspective view thereof,

FIGURE 3 is a front elevational view thereof, and

FIGURE 4 is a back elevational view thereof.

The side, which is not shown, is a mirror image of the side shown.

The design is characterized by a unitary back and headrest with extensions of the back projecting forward and overlapping with vertically projecting portions of the unitary seat and arms.

I claim:

The ornamental design for a reclining chair, substantially as shown and described.
